THERMAL RELAY AND CONSTANT GAP
SPACERHarry A. Pearl, Dayton, Ohio, and Merritt Allen
Rudner, Camden, N. J.

Application November 14, 1951, Serial No. 256,354

19 Claims. (Cl. 200—122)

(Granted under Title 35, U. S. Code (1952),
sec. 266)

1

The invention described herein may be manufactured and used by or for the Government for governmental purposes without payment to us of any royalty thereon.

This invention relates to a thermal contact making or breaking device capable of maintaining a predetermined fixed distance between electrical contacts while exposed to any variation of ambient temperatures within a wide temperature range, such as -65°C . to $+400^{\circ}\text{C}$. by the use of positive and negative thermal coefficient of expansion materials. These materials are firmly attached to each other in such a manner that the expansion of one material will effectively be counterbalanced by the contraction of the other. The switching or relay action is controlled by application of heat to one or more members of the balanced system in such a way as to cause a variation in the original predetermined fixed distance by an amount sufficient to make the electrical contacts touch or separate, thereby opening or closing an electrical circuit. The delay relay action is governed by the rate of the applied heating or the distribution of the heating coil on the said one or more members.

The object of this invention is to provide a thermal relay or switch which is capable of satisfactory operation over a relatively wide ambient temperature range without being affected by ambient temperature variations.

Another object of this invention is to provide a thermal relay or switch which contains no moving parts and which, therefore, is reliable and easy to construct and essentially insensitive to the effects of excessive vibration and shock.

Still another object of this invention is to provide a thermal relay or switch which is hermetically sealed so as to avoid the adverse effects of dust and dirt, salt sea atmosphere, humidity, corrosion and high altitude, and which allows the use of a vacuum or inert gas to increase contact carrying potentials.

A further object of this invention is to obtain a thermal relay or switch which may be readily modified so as to be adaptable for various uses, such as an overload make or break relay, underload make or break relay, combination overload and underload make or break relay, or a differential type relay, and whose time delay is readily adjusted by simple means to give long or short periods of time delay.

In the accompanying drawings:

Figure 1 is a central longitudinal section of a device illustrating the basic principles of the subject invention;

2

Figure 2 is a central longitudinal section of a modification of the device shown in Figure 1;

Figure 3 is a central longitudinal section of a thermal relay switch, embodying the invention;

Figure 4 is a central longitudinal section of another embodiment of the invention, in which two compound members, instead of one, are used;

Figure 5 is a central longitudinal section of still another embodiment of the invention utilizing lever action to provide spacing of the metallic contacts;

Figure 6 is a central longitudinal section of a further embodiment of the invention in which the negative thermal coefficient of expansion elements are U-shaped;

Figure 7 is a central longitudinal section of a further embodiment of the invention in which the negative thermal coefficient of expansion elements are S-shaped;

Figure 8a is a ternary diagram for systems comprising lithia, alumina and silica;

Figure 8b is a ternary diagram showing in detail the cross-hatched portion of Figure 8a and showing areas of negative and zero thermal expansion in Lithia-Alumina-Silica systems.

Like numerals refer to like parts throughout the several views of the drawings.

Referring to Figure 1, which illustrates the basic principles of the subject invention, A is a compound member, comprising two portions or elements, 1 and 2. Element 1 is composed of a material having a positive temperature coefficient of expansion which may be metallic or non-metallic. Element 2 which is firmly attached to element 1, is composed of a material having a negative temperature coefficient of expansion. This negative coefficient of expansion material may be a ceramic of the lithia-alumina-silica system, such as spodumene or petalite. Element 1 is firmly fixed to a holder member 6 having an effectively zero thermal coefficient of expansion. Referring now to Figure 8 of the drawing, a portion of a complete conventional ternary diagram of the system comprising alumina (Al_2O_3), silica (SiO_2), and lithia (Li_2O) is shown. The diagram shown in Figure 8b represents that portion of the diagram of Figure 8a shown cross-hatched.

The two cross-hatched areas A and B in Figure 8b are areas of negative or zero thermal expansion in lithia-alumina-silica systems. That is, any material having the percentages of lithia, alumina and silica indicated in a cross-hatched area is characterized by either a negative thermal coefficient of expansion or a zero thermal coefficient. The exact areas over which the coefficient

is zero rather than negative are not shown, but it is sufficient here to say that a material having a zero thermal coefficient may be found at some points within the cross-hatched areas A and B, the same being true as to materials having negative thermal coefficients. As an example, points P, S and E are examples of the negative thermal coefficient materials petalite ($\text{Li}_2\text{O} \cdot \text{Al}_2\text{O}_3 \cdot 8\text{SiO}_4$), spodumene ($\text{Li}_2\text{O} \cdot \text{Al}_2\text{O}_3 \cdot 4\text{SiO}_2$), and eucryptite ($\text{Li}_2\text{O} \cdot \text{Al}_2\text{O}_3 \cdot 2\text{SiO}_2$), respectively. The zero coefficient of expansion material may also be a ceramic produced by properly combining and processing positive and negative coefficient of expansion ceramic materials.

Returning now to Figure 1, elements 1 and 2 may be of the same or different lengths and geometric shapes. The lengths of elements 1 and 2 are chosen so that the length of element 1 multiplied by the numerical value of its coefficient of thermal expansion is equal to the length of element 2 multiplied by the numerical value of its coefficient of thermal expansion. Therefore, member A does not effectively change its length even though exposed to wide variations of ambient temperatures in the range of -65°C . to $+400^\circ\text{C}$. Although holder member 6 is preferably made of a material having a zero thermal coefficient of expansion, it may also be made of materials so fabricated that its length does not change with variations in ambient temperature. The net effect will be to maintain a predetermined fixed gap 5 over the aforementioned temperature range. The geometric shapes of elements 1 and 2 are selected on the basis of their thermal conductivities. For best results, elements 1 and 2 should assume the temperature of their environment at the same rate. Since the lengths of elements 1 and 2 are determined by their thermal coefficients of expansion their masses will be varied so that they assume the temperature of their environment at the same rate.

All considerations so far have been limited to maintaining a fixed predetermined gap 5 under wide variations in temperature. The switching or relay action is controlled by applying heat to element 1 or element 2 in such manner as to localize the heat to one element as much as possible. If the heat is applied to element 1 which has the positive thermal coefficient of expansion, the gap 5 will close but if the heat is applied to element 2, which has a negative coefficient, the gap will open. For relay or switching purposes, holder member 6 may be constructed as described in the preceding paragraph, or may be made of materials so fabricated that its change of length is insufficient to open or close the gap, as the case may be, in the event that no thermal energy is applied to the compound member. To sum up, holder member 6 need not be constructed of a single material having a zero thermal coefficient of expansion but may be of such construction and composition as to have an effectively zero thermal coefficient of expansion. This controlled variation is used to complete or open electrical circuits. The rate at which heat is applied will govern the delayed time action of the relay.

Member A is not limited to two materials, but may be composed of any convenient number of materials provided the composite materials are so fabricated that its length does not effectively change with ambient temperature over the range specified previously.

The positions of elements 1 and 2 are inter-

changeable. In relays, the heat can be applied by electrically energized coils or other suitable devices.

5 The expansion, contraction materials may be used as conductive members for establishing electrical contacts. When the material is a metal alterations may or may not be necessary depending upon the current carrying capacity. When the material is a non-metal it can be 10 coated with an adherent conductive coating to form an electrically suitable contact.

Figure 2 discloses the modification of the device described in Figure 1 in which two compound members A and B instead of one, are used.

15 Member A is composed of an element 1, made of a material having a negative coefficient of expansion, firmly attached to an element 2, made of a material having a positive coefficient of expansion. Member B is similarly composed of an element 3, having a negative coefficient of expansion, firmly attached to the element 4 which has a positive coefficient of expansion.

20 Members A and B, as well as elements 1, 2, 3 and 4 may be of equal or unequal lengths or 25 geometric shapes.

The basic operation of the relay will not be altered if the positions of elements 1 and 2 are interchanged or the positions of elements 3 and 4 are interchanged.

30 Members A and B are each firmly attached at one end to a base member 6 made of a material having an effectively zero coefficient of expansion so as to maintain a predetermined gap 5 under the temperature range of -65°C . to $+400^\circ\text{C}$, as shown in Figure 2.

35 The lengths and geometric shapes of elements 1, 2, 3 and 4 are selected by the use of the same criteria as specified for Figure 1.

All considerations so far have been limited to maintaining a fixed predetermined gap 5 under wide variations of temperature. The switching or relay action is controlled by applying heat to members A or B, or both, in such a way as to localize the heat to one or more elements 1, 2, 3 or 4. The elements to be heated should be such as to cause an unbalanced expansion which will either close or open gap 5. To illustrate: Where elements 1 and 3 are negative coefficient of expansion materials and elements 2 and 4 are positive coefficient of expansion materials, if 40 heat is applied to element 1 or element 3, or both, the gap 5 will open, while if heat is applied to element 2 or element 4, or element 2 and element 4, the gap 5 will close. The controlled variation of gap 5 is used to close or open electrical circuits. The rate at which heat is applied will govern the delay time action of the relay.

45 Referring to Figure 3 of the drawing, a practical embodiment of the fundamental principles set forth in connection with Figures 1 and 2 is shown. Metallic contact 7 is welded or otherwise fastened to positive thermal coefficient of expansion element 4, which is, in turn, securely fastened to negative coefficient of expansion element 3, with the entire assembly fastened securely to an effectively zero coefficient of expansion member 6 to maintain a constant gap 5 when not energized. Metallic contact 7' is 50 welded or otherwise fastened to member 6 and mounted collinearly with contact 7. Contact leads 8 and 9 are brought out of a hermetically sealed glass enclosure 10 through a ring seal 11. Glass wool 12 is packed between the relay assembly 3, 4, 6, 7, 7' and the glass enclosure 10 to aid 55 in positioning the assembly and to render the

assembly relatively insensitive to shock or vibration. Coil heater leads 13 and 14 are brought out through ring seal 11' and are attached to heater coil 15 which conducts heat when energized to the positive thermal coefficient of expansion element 4, which expands at a predetermined rate moving the two metal contacts 7 and 7' together and thereby completing the circuit between leads 8 and 9. When de-energized, member 4 contracts at a predetermined rate causing contacts 7 and 7' to open, thereby breaking the circuit between leads 8 and 9. Heater 15 may be a resistance metal such as silver, copper, palladium, platinum, semiconductors, or other conductors capable of converting electrical energy into thermal energy.

Referring to Figure 4, two metallic contacts 7 and 7' are welded or otherwise fastened to positive thermal coefficient of expansion elements 2 and 4 which, in turn, are attached to negative thermal coefficient of expansion elements 1 and 3, with the entire assembly fastened securely to an effectively zero thermal coefficient of expansion member 6 to maintain a constant gap 5 when not energized. Elements 1 and 3 are shown as having a threaded end portion which can be screwed into tapped holes in member 6. Other means of mounting may, of course, be used. Contact leads 8 and 9 are brought out of the hermetically sealed glass enclosure 10 through a ring seal 11. Elements 1 to 4 may be in various configurations, other than straight. Staking compound 17 may be used to aid in securing the compound members A and B to the holder member 6. Glass wool 12 is packed around the relay assembly 1 through 7, as pointed out previously in connection with Figure 3. Coil heated leads 13 and 14 pass through ring seal 11' and are attached to heaters 15 and 16 which conduct heat, when energized, to the positive thermal coefficient of expansion members 2 and 4 which expand at a predetermined rate moving the two metallic contacts 7 and 7' together and thereby completing the circuit between leads 8 and 9. When de-energized members 2 and 4 contract at a predetermined rate causing contacts 7 and 7' to open, thereby breaking the circuit between leads 8 and 9.

By carefully selecting the materials of elements 1, 2, 3 and 4 the relay may be temperature compensated over the range of from -65° C. to +400° C. to the extent that the gap 5 remains constant regardless of any external ambient temperature within the compensated range.

Referring to Figure 5, two metallic contacts 7 and 7' are welded or fastened to zero thermal coefficient of expansion members 18 and 19 which in turn are attached to positive thermal coefficient of expansion elements 2 and 4. Elements 2 and 4 are attached to negative thermal coefficient of expansion elements 1 and 3 with the entire assembly fastened securely to an effectively zero thermal coefficient of expansion member 6 to maintain zero gap 5 when not energized. Contact leads 8 and 9 are brought out of the hermetically sealed enclosure 10 through a header type seal 11. Two lever arms, 16 and 19, are mounted on member 6 by means of two pins 21, 21, as shown in Figure 5. Staking compound 17 may be used to aid in securing compound members A and B to the holder member 6. A return spring 23 is used to aid in positioning and maintaining a constant gap. Coil heater leads 13 and 14 are brought out through seal 11 and are attached to heaters 15 and 16 which con-

duct heat, when energized, to the positive thermal coefficient of expansion elements 2 and 4. Elements 2 and 4 then expand at a predetermined rate, moving the two lever arms 18 and 19, causing the two metallic contacts 7 and 7' to move apart, and thereby breaking the circuit between leads 8 and 9. When de-energized, elements 2 and 4 contract at a predetermined rate causing contacts 7 and 7' to close thereby completing the circuit between leads 8 and 9. By carefully selecting the materials of items 1, 2, 3, 4, 6, 18 and 19, the relay may be temperature compensated over the range of from -65° C. to +400° C. to the extent that the gap 5 remains constant regardless of any external ambient temperature within the compensated range. Moving spring 23 below the fulcrum would result in a normally open relay which would be closed by means of coils on elements 1 and 3.

Referring to Figure 6, this embodiment is similar to the one shown in Figure 4 and described previously, except that the portions or elements 1 and 3 of the assembly 1 through 4 are U-shaped for space considerations. Portions 2 and 4 are screwed into or otherwise attached to, one end of portions 1 and 3, respectively. The entire assembly 1 through 4 is fastened securely to an effectively zero thermal coefficient of expansion member 6, as clearly shown in Figure 6.

The embodiment of Figure 7 is similar to that of Figure 6, differing from the one shown in Figure 6 only in that the configuration of the elements 1 and 3 are S-shaped rather than U-shaped, and in that the leads are brought out from a common seal 11, in the manner shown in the embodiment of Figure 5. The operation is identical to that of Figure 6, previously described.

We claim:

1. A contact making and breaking device comprising a compound member composed of materials some of which have a positive thermal coefficient of expansion and others of which have a negative thermal coefficient of expansion and so fabricated that the length of said compound member does not change with wide variations in ambient temperature, a holder member having an effectively zero thermal coefficient of expansion, said compound member having one end thereof firmly attached to one end of said holder member and having the other end thereof unsupported and mounted adjacent the other end of said holder member so that a predetermined fixed gap is maintained between said unsupported end of said compound member and said other end of said holder member over a wide range of ambient temperatures, means for applying heat to a portion only of said compound member so that said gap is either closed or opened, depending upon whether said portion has a positive or a negative thermal coefficient of expansion, respectively.

2. A contact making and breaking device comprising a compound member whose length is independent of ambient temperature and consisting of a first element made of a material having a positive thermal coefficient of expansion and a second element made of a material having a negative thermal coefficient of expansion, said first and second elements being fixedly attached to one another at one end thereof, a holder member having an effectively zero thermal coefficient of expansion, the other end of one of said elements being connected to one end of said holder member and the other end of the other of said

elements being mounted adjacent the other end of said holder member and so positioned with respect thereto as to form a gap therebetween which is independent of ambient temperature, and means for supplying thermal energy to one element only of said compound member to cause the latter to change in length, whereby said gap spacing is varied in response to said means for supplying thermal energy while remaining insensitive to variations in ambient temperature.

3. A contact making and breaking device comprising a compound member composed of a first portion having a positive thermal coefficient of expansion, a second portion having a negative thermal coefficient of expansion, said first and second elements being fixedly attached to one another at one end thereof, so that the length of said compound member is independent of ambient temperature, a holder member having an effectively zero thermal coefficient of expansion, said compound member having the other end of said first portion attached to one end of said holder member and the other end of said second portion so positioned with respect to the other end of said holder member as to form a gap which remains fixed regardless of ambient temperature, and means for applying heat to said first portion only, thereby causing said compound member to expand and close said gap.

4. A contact making and breaking device comprising a compound member composed of a first portion having a positive thermal coefficient of expansion, a second portion having a negative thermal coefficient of expansion, said first and second elements being fixedly attached to one another at one end thereof, so that the length of said compound member is independent of ambient temperature, a holder member having an effectively zero thermal coefficient of expansion, said compound member having the other end of said first portion attached to one end of said holder member and the other end of said second portion so positioned with respect to the other end of said holder member as to form a gap which remains fixed regardless of ambient temperature, and means for applying heat to said second portion only, thereby causing said compound member to contract and open said gap.

5. A contact making and breaking device comprising a compound member composed of a first portion having a positive thermal coefficient of expansion, a second portion having a negative thermal coefficient of expansion, said first and second elements being fixedly attached to one another at one end thereof, so that the length of said compound member is independent of ambient temperature, a holder member having an effectively zero thermal coefficient of expansion, said compound member having the other end of said second portion attached to one end of said holder member and the other end of said first portion so positioned with respect to the other end of said holder member to form a gap which remains fixed regardless of ambient temperature, and means for applying heat to said first portion only thereby causing said compound member to expand and close said gap.

6. A contact making and breaking device comprising a compound member composed of a first portion having a positive thermal coefficient of expansion, a second portion having a negative thermal coefficient of expansion, said first and second elements being fixedly attached to one another at one end thereof, so that the length of said compound member is independent of ambient

temperature, a holder member having an effectively zero thermal coefficient of expansion, said compound member having the other end of said second portion attached to one end of said first holder member and the other end of said first portion so positioned with respect to the other end of said holder member as to form a gap which remains fixed regardless of ambient temperature, and means for applying heat to said second portion only thereby causing said compound member to contract and open said gap.

7. A contact making and breaking device having a hermetically sealed enclosure comprising a compound member whose length is independent of ambient temperatures and consisting of a first element made of a material having a positive thermal coefficient of expansion and a second element made of a material having a negative thermal coefficient of expansion, said first and second elements being fixedly attached to one another at one end thereof, a holder member having an effectively zero thermal coefficient of expansion, the other end of one of said elements being connected to one end of said holder member and the other end of the other of said elements being mounted adjacent the other end of said holder member and so positioned with respect thereto as to form a gap therebetween which is independent of ambient temperature, a first metallic contact attached to said other end of the other of said elements and a second metallic contact attached to said other end of said holder member, a pair of contact leads, one connected to each of said metallic contacts and passing externally of said contact making and breaking device through a seal in said enclosure, and means for supplying thermal energy to one element only of said compound member, said means comprising a coil surrounding said one element and coil heater leads attached to the coil and passing externally of said contact making and breaking device through a seal in said enclosure, whereby said gap spacing is varied in response to said means for supplying thermal energy while remaining insensitive to variations in ambient temperature.

8. A contact making and breaking device comprising first and second compound members whose lengths are independent of ambient temperature and each consisting of a first element having a positive thermal coefficient of expansion and a second element having a negative thermal coefficient of expansion, said first and second elements of each compound member being fixedly and collinearly attached to one another at one end thereof, a holder member having an effectively zero thermal coefficient of expansion, said first compound member being attached to one end of said holder member and said second compound member being attached to the other end of said holder member in such manner as to form a gap between the unattached ends of said compound members which is independent of ambient temperature, and means for supplying thermal energy to one element only of each of said compound members, causing the latter to change in length, whereby the gap spacing is varied in response to said means for supplying thermal energy while remaining insensitive to variations in ambient temperature.

9. A contact making and breaking device having a hermetically sealed enclosure comprising first and second compound members whose lengths are independent of ambient temperature and each consisting of a first element having a positive thermal coefficient of expansion and a second

element having a negative thermal coefficient of expansion, said first and second elements of each compound member being fixedly and collinearly attached to one another at one end thereof, a holder member having an effectively zero thermal coefficient of expansion, said first compound member being attached to one end of said holder member and said second compound member being attached to the other end of said holder member in such manner as to form a gap between the unattached ends of said compound members which is independent of ambient temperature, a metallic contact attached to each of said unattached ends of said compound members, a pair of contact leads, one connected to each of said metallic contacts and passing externally of said contact making and breaking device through a seal in said enclosure, and means for supplying thermal energy to one element only of each of said compound members, said means comprising a pair of heating coils, one surrounding each of said one elements of said compound members, said coils being connected in parallel, and coil heater leads attached to said coils and passing externally of said contact making and breaking device through a seal in said enclosure and causing the latter to change in length, whereby the gap spacing is varied in response to said means for supplying thermal energy while remaining insensitive to variations in ambient temperature.

10. A contact making and breaking device as recited in claim 9 in which said second elements are U-shaped.

11. A contact making and breaking device as recited in claim 9 in which said second elements are S-shaped.

12. A contact making and breaking device having a hermetically sealed enclosure comprising first and second compound members whose lengths are independent of ambient temperature and each consisting of a first element having a positive thermal coefficient of expansion and a second element having a negative thermal coefficient of expansion, said first and second elements of each compound member being fixedly and collinearly attached to one another at one end thereof, a holder member having an effectively zero thermal coefficient of expansion, said first compound member being attached to one end of said holder member and said second compound member being attached to the other end of said holder member, first and second lever members pivotally mounted on said holder member and having one end of said first lever member engaging the unattached end of said first compound member and a corresponding end of said second lever member engaging the unattached end of said second compound member, the other ends of said lever members adapted to lie adjacent one another so as to form a gap therebetween, a spring having one end connected to said first lever member and the other end connected to said second lever member to aid in positioning and maintaining constant said gap, a pair of metallic contacts, one fastened to each of said other ends of said lever members, a pair of contact leads, one connected to each of said metallic contacts and passing externally of said contact making and breaking device through a seal in said sealed enclosure, said gap being insensitive to changes in ambient temperature, means for supplying thermal energy to one element only of each of said compound members causing the latter to change in length and actuate said lever members against the bias

of said spring, whereby the gap spacing is varied in response to said means for supplying thermal energy while remaining insensitive to variations in ambient temperature.

5. 13. A contact making and breaking device as recited in claim 12 in which said means for supplying thermal energy comprises two serially connected coils, each coil surrounding said one element of the respective compound member, and coil heater leads connected to said coils and passing externally of said contact making and breaking device through said seal.

14. A thermal relay comprising a composite member in the form of a loop having a gap 15 therein, said loop consisting of sections made of materials having positive, negative and zero coefficients of thermal expansion, with each junction between sections having coefficients of opposite sign including the axis passing through the gap faces of said member and with the lengths of the sections having positive and negative coefficients proportioned relative to said coefficients so that an overall change in the temperature of said member produces no relative 20 movement of said faces, means for producing relative movement of said faces comprising means for applying heat exclusively to one of the said materials having positive and negative coefficients, a pair of electrical contacts, and means mechanically coupling said contacts to said faces for actuation thereby.

15. A thermal relay comprising a base member made of a material having a coefficient of thermal expansion of zero, a pair of oppositely disposed contacts, means for supporting said contacts on said base member, said supporting means comprising serially arranged sections each made of one of two materials having thermal coefficients of expansion of opposite sign, with the axis passing through said contacts also passing through at least a part of each section and through each junction between sections of opposite sign, the lengths of said sections being proportioned relative to said coefficients so that 40 an overall change in the temperature of said relay produces no relative movement of said contacts, and means for producing relative movement of said contacts comprising means for applying heat exclusively to one of said two materials.

16. A thermal relay comprising a base member made of a material having a coefficient of thermal expansion of zero, a pair of oppositely disposed contacts one of which is mounted on 55 said base member, means for supporting the other of said contacts on said base member, said means comprising an attaching structure consisting of a pair of serially joined sections made of materials having coefficients of thermal expansion of opposite signs, the axis passing through said contacts also passing through at least a portion of each of said sections and the lengths of said sections being proportioned relative to said coefficients so that an overall change 60 in the temperature of said relay produces no relative motion of said contacts, and means for producing relative motion of said contacts comprising means for applying heat to one only of said sections.

17. A thermal relay comprising a base member made of a material having a coefficient of thermal expansion of zero, a pair of oppositely disposed contacts, similar means for attaching said contacts to said base member, each attaching means comprising a pair of serially joined

11

sections made of materials having coefficients of thermal expansion of opposite signs, the axis passing through said contacts also passing through at least a portion of each of said sections, the lengths of the sections of both attaching means being proportioned relative to said coefficients so that an overall change in the temperature of said relay produces no relative motion of said contacts, and means for producing relative motion of said contacts comprising means for applying heat to those sections having coefficients of like sign.

18. Apparatus as claimed in claim 17 in which the section adjacent said base member in each attaching means is U-shaped.

19. Apparatus as claimed in claim 17 in which

5

12

the section adjacent said base member in each attaching means is S-shaped.
